ATTORNEY.

UNITED STATES PATENT OFFICE.

FRIEDRICH SCHEPPMANN, OF TOLUCA, MEXICO.

STOCK FEEDING AND WATERING DEVICE.

Application filed May 3, 1922. Serial No. 558,281.

To all whom it may concern:

Be it known that I, FRIEDRICH SCHEPPMANN, a citizen of Germany, residing at Toluca, Mexico, have invented certain new and useful Improvements in Stock Feeding and Watering Devices, of which the following is a specification.

This invention appertains to certain new and useful improvements in feed and water cribs, troughs or the like generally, and more particularly to a type of the same adapted for use in railroad cars, transports and the like for the feeding and watering of stock during their shipment from one point to another.

The principal object of the invention is to provide for a crib or trough of the class mentioned, and one of an extremely durable but comparatively light weight construction having the parts thereof arranged whereby to be readily and quickly set up in position against a supporting wall or partition, or collapsed to a substantially flat state against the wall or partition when not in use, or to be removed from the wall or partition and collapsed or folded into a compact bundle or package of the size readily portable from one point of use to another, or capable of being packed in a relatively small space for storage or shipping purposes.

With the foregoing and other objects in view, the invention resides in the certain new and useful construction and arrangement of parts as will be hereinafter more fully described, set forth in the appended claims, and illustrated in the accompanying drawings, in which:—

Figure 1 is a top plan view of a freight car or the like with a portion of the roof thereof broken away to show the manner of positioning a preferred embodiment of the invention within the interior thereof,

Figure 2 is an enlarged transverse section through the improved feed or water crib or trough and the wall of a freight car or the like upon which it is supported in position,

Figure 3 is an enlarged fragmentary vertical section taken on the line 3—3 of Fig. 2, and with a part thereof in front elevation and a portion of the latter broken away to show the manner of securing the canvas or sail cloth material on the crib or trough to the flexible cable or the like by means of

which the latter is moved to and from its operative or inoperative positions,

Figure 4 is a fragmentary horizontal section through one wall of a freight car or the like, and showing the crib or trough as it appears in its collapsed or inoperative position,

Figure 5 is a fragmentary perspective view of the supporting plate used in connection with the crib or trough, especially in the application of the same for use in freight cars and the like,

Figure 6 is a perspective view of one of the curved bars for retaining the fabric, such as canvas, linen or the like, in its trough forming condition,

Figure 7 is a perspective view of one of the bars for retaining the rear wall of the canvas or sail cloth in its trough forming position, and

Figure 8 is a perspective view of a pivot supporting block and the securing means for the latter.

Referring to the drawing, wherein similar characters of reference designate corresponding parts throughout the several views thereof, the numeral 10 indicates a suitable length of flexible material, such as canvas, water proofed linen or the like, having a width that, when properly arranged in the trough form as desired, a proper width and depth will be provided for in the finished crib or trough suitable for the placing therein of a supply of feed or water sufficient for the feeding and watering of a given number of horses, cattle or other animals being transported in a freight car or the like, the compartment of a transport ship, or in any other manner of use. The rear wall 11 of the feed or water crib or trough is formed by one of the longitudinal edge portions of the material 10 being clamped between front and rear sets of vertically disposed metal bars or strips 12 and 13, arranged in pairs, one equidistantly spaced from the other, the bars or strips of each pair of the same being clamped at opposite sides of the material 10, by means of a plurality of bolts or the like 14. Passing through the upper and lower ends of each pair of the bars or strips 12 and 13, are bolts 15 and 16, respectively, each having their forward or headed ends engaged in blocks or the like 17 and 18, respectively, and acting to clamp the same in position against the outer faces of

the front bars or strips 12. The rearwardly directed threaded ends of the bolts 15 and 16 are first passed through spacing sleeves 19 and then through aligned openings in 5 metal supporting strips 20, and have their extreme rear ends engaged by nuts 21. By the use of the spacing sleeve 19, the several pairs of bars 12 and 13 are uniformly spaced at the front side of the supporting strips 20 10 in a manner that the rear wall of the material 10 is disposed in vertical parallel relation with respect to the wall of the stock car *a*, substantially as is shown.

Pivoted to the underside of each of the 15 lower blocks 18, by means of pivot pins 22, are forwardly and upwardly curved bars or strips 23, each having their forward or upper ends angularly bent to provide forwardly projecting horizontal portions 24, to 20 which are secured, as by means of bolts or the like 25, the forward ends of a corresponding number of horizontally disposed bars or strips 26, which are pivoted at their inner or rear ends to the upper face of the 25 upper blocks 17 by means of pivot pins 27. These pivoted division frames, formed by the curved bars or strips 23 and the horizontal bars or strips 26, are equidistantly spaced apart correspondingly with the pairs 30 of clamping bars or strips 12 and 13, and are connected in their normally spaced relation by means of a cable or rope 28, extending between the same, the opposite free ends of the latter being extended for a distance beyond 35 the outer and oppositely disposed of the frames for purposes which will be hereinafter more fully explained. The forward portion of the material 10 is stretched in a forward and upward direction, from the 40 lower ends of the bars or strips 12 and 13, and is secured against the outer faces of the curved bars or strips 23, by means of bolts, rivets or the like 29, at points inwardly of the extreme forward or front longitudinal 45 edge 30 of the material 10, while this extreme forward or front edge 30 is trained outwardly over and around the cable or rope 28, and is secured to the main body of the material in any suitable or desired manner, as by stitching the same together. The 50 cable or rope 28 is secured in position beneath the horizontally disposed portions 24, of the curved bars or strips 23, by means of bolts 25 being passed through the same and the edge of the material engaged around the cable or rope, substantially as is shown. The opposite ends of the crib or trough thus 55 constructed and arranged, are closed by means of end walls 31, of the same material as the body portion 10, and the adjacent edges of the same are joined together by cement, stitching or the like, in a manner to provide water-tight seams or joints therebetween.

60 65 In the specific application of the crib or

trough to the interior of a freight car or cattle car as illustrated in the drawing, the body of the car being indicated as at *a*, and with the crib or trough secured in position, the metal supporting strips 20 are to be suspended in position along one of the longer sides of the interior of the body of the car *a*, by means of pairs of spaced slots 32, formed inwardly from the opposite ends of the strips 20, being engaged over the headed or hooked ends of similarly arranged pairs of spaced hangers or hooks 33 driven into the side wall *b* of the car body *a*, and by reason of the length of the crib or trough, one pair of these hangers or hooks are disposed at opposite sides of the central side door opening *c*, whereby the crib or trough is centered on the wall *b* with respect to the opposite ends of the car body *a*. As shown in Fig. 1, after the crib or trough has been hung in position 70 within the car body *a*, and it is desired to arrange the same for the feeding or watering of horses, cattle or other animals, being transported within the car, the trough frames formed by the curved bars or strips 23 and the straight bars or strips 26, are swung to position directly inwardly of the car and at right angles to the wall thereof, when the material 10 will be stretched into a smooth open through-like condition, and 75 ready for the placing within the same of the feed or water. To assure of the crib or trough remaining in its open and operative position, the opposite free ends of the cable or rope 28 are secured to hooks or staples 80 34, which are driven into the side wall *b* of the car body *a* for the purpose. After the feeding or watering of the animals has been accomplished, and it is desired to leave the crib or trough in position for the subsequent 85 feeding or watering period, the outer curved wall of the crib or trough is to be collapsed in substantially flat condition against its inner wall by the unfastening of the opposite ends of the cable or rope 28, and swinging 90 the trough frames on their pivots 22 and 27, all in one direction, and back against the wall 11, when the proper end of the cable or rope 28 will be again fastened to its hook or staple 34, substantially as is shown in 95 Fig. 4, whereby to retain the frames in their folded position.

When it is desired to remove the crib or trough from its position within the car, the cable or rope end or ends are unfastened 100 from the hooks or staples 34, and the strips 20 lifted from the supporting hooks 33. The crib or trough may now be folded into a compact bundle or package as will be obvious from the flexible construction of the same 105 throughout its length.

From the foregoing, it will be readily apparent that the invention provides for a feed or water crib or trough of a type capable of universal use, particularly in army and 110

navy or private transport services, where larger numbers of horses or other animals are to be fed and watered, and that the same can be manufactured cheaply, and will be durable for use in long periods of service, and of light weight so as to be readily portable, and, in its collapsed and folded state, can be conveniently packed in a relatively small space for storage or shipment.

10 In light of the foregoing, it is well understood that, while a preferred embodiment of the device has been described and illustrated herein in specific terms and details of construction and arrangement, various 15 changes in and modifications of the same may be resorted to without departing from the spirit of the invention, or the scope of the claims appended hereto.

Having thus described the invention, what 20 is claimed as new is:—

1. A stock feeding and watering device comprising a trough-shaped body of a flexible material, a support, frames carried by said body and acting to normally retain the 25 same in non-collapsed position, and means for pivotally securing said frames to said support, whereby the same may be swung in either direction from their normally operative positions to collapse the body against 30 said support.

2. A stock feeding and watering device comprising a trough-like body of a flexible

material, supporting means for said body, a plurality of equidistantly spaced frames carried by said body and normally acting 35 to retain the same in non-collapsed position, means for pivotally securing said frames to said supporting means whereby the same may be swung in either direction from their normally operative positions to collapse the 40 body against said support, and means for actuating said frames to and from operative position.

3. A stock feeding and watering device comprising a trough-like body of a flexible 45 material, supporting means for said body, a plurality of equi-distantly spaced frames carried by said body and normally acting to retain the same in non-collapsed position, means for pivotally securing said frames to 50 said supporting means whereby the same may be swung in either direction from their normally operative positions to collapse the body against said support, means engageable with said supporting means for suspending the same and said body in operative position, and means connecting said frames in their normally spaced positions, and operable for actuating said frames to and from 55 their normally operative positions. 60

In testimony whereof, I affix my signature hereto.

FRIEDRICH SCHEPPMANN.
